UNITED STATES PATENT OFFICE.

ALBIN BERTHOLD HELBIG, OF BERLIN, GERMANY.

SETTING OR MOUNTING FOR ALL KINDS OF REVOLVING DRUMS.

Application filed November 4, 1924. Serial No. 747,874.

To all whom it may concern:

Be it known that I, ALBIN BERTHOLD HELBIG, a citizen of Germany, and resident of Berlin, Germany, have invented certain new and useful Improvements in Settings or Mountings for All Kinds of Revolving Drums, of which the following is a specification.

This invention relates to an improved setting or mounting for all kinds of revolving drums, such for instance as are used in furnaces or in drying machines. Heretofore it has been the practice to provide such drums with circumferential bands or rings for rolling contact upon suitable rotatably mounted rollers or supports.

It has heretofore been quite difficult to arrange the guiding surfaces of the drums exactly parallel with the rotatable rollers or supports as it is practically impossible to correct errors due to the considerable distance between the guiding bands or rings on the drum. It has been customary to remove the drum and place the same in a lathe and turn down the guiding surfaces thereof. This, however, is practically impossible in the case of very large drying drums or revolving furnaces.

It is, therefore, the primary object and purpose of the present invention to provide an improved drum setting wherein the above difficulty is effectively overcome. My invention further provides means whereby the supporting rollers for the drum may be very easily and quickly adjusted so as to maintain the contacting surface thereof exactly parallel with the surface of the ring or band on the drum.

In one practical embodiment of the invention, I propose to arrange the rotatable rollers or supports upon which the drum is set or mounted, for universal swiveling or pivoting movement so that these rollers will automatically follow the drum in any deflection thereof from its true axial position.

It is another object of the invention to provide improved means for continuously and automatically lubricating the various parts of the drum rollers or supports.

With the above and other objects in view, the invention consists in the improved drum setting, and in the form, construction and relative arrangement of the several parts thereof, as will be hereinafter more fully described, illustrated in the accompanying

drawings and subsequently incorporated in the subjoined claims.

In the drawings wherein I have illustrated one simple and satisfactory embodiment of the invention and in which similar reference characters indicate corresponding parts throughout the several views:

Figure 1 is a diagrammatic view showing a setting for a revolving drum of large capacity, wherein the guide rings or bands on the drum are arranged at a distance of from 10 to 25 meters from each other;

Figure 2 is a view of a portion of the drum having a band thereon positioned at right angles to Figure 1 and showing the drum deflected from its positive normal position as may be occasioned by buckling of the drum due to uneven heating or other causes;

Figure 3 is an enlarged side elevation of one of the drum sets or rollers;

Figure 4 is a longitudinal section thereof;

Figure 5 is a detail section showing another guide roller or bearing used at each end of the drum for preventing axial shifting movement thereof; and

Figure 6 is a detail sectional view on an enlarged scale of the drum supporting roller shown in Figure 4;

Referring in detail to the drawings, 5 designates the drum, such as is used in large capacity revolving furnaces, said drum being provided with the guide bands or rings 6 circumscribing the drum adjacent its opposite ends. These rings are engaged upon the drum sets or supports, which in the present instance, are indicated generally at 7 and arranged in pairs suitably spaced from each other on opposite sides of the longitudinal center line of the drum.

As shown in Figures 3 and 4 of the drawings, each of the drum supports 7 consists of a roller 8 rigidly clamped and secured between the two semi-spherical members 9 by means of the bolts indicated at 10. This roller is supported by a suitable roller bearing 11 upon a fixed shaft 12. At opposite sides of the roller inner and outer guide members 13 and 14 respectively, are arranged upon said shaft, said guide members having substantially parallel curved flanges between which the members 9 are movably guided. Spacing collars 15 surround the shaft 12 between the members 13 and 14. The shaft is provided with threaded sections receiving the nuts 16 whereby the parts 13,

14 and 15 are clamped together and rigidly held in fixed position upon said shaft. The inner face of each of the members 9 carries an annular packing ring or gasket 17 of 5 felt or other suitable material having sliding contact upon the outer convex surface of one of the members 13.

The opposite ends of the shaft 12 are supported by bearing pedestals 18, the upper 10 ends of which are bifurcated or slotted to receive the adjustable wedge members 19, the upper surfaces of which are beveled or inclined and contact with the correspondingly inclined lower faces of the bearing 15 blocks 20. The upper faces of these blocks are provided with grooves to receive rollers 21 and the shaft 12 at each end thereof has a transverse groove 22 cut in the underside thereof to receive the upper portions of these 20 rollers. Thus it will be understood that the shaft at its ends has rocking engagement upon the rollers 22 so that in the adjustment of either of the wedge members 19 with respect to the other, the axis of the 25 shaft may assume any desired angular position relative to a horizontal plane.

As shown in Figure 6 of the drawings, one 30 end portion of the shaft 12 is provided with an axially extending oil duct 23, the inner end of which communicates with a transverse passage 24 opening upon the periphery of the shaft. The open end of said passage registers with an orifice 25 formed in the hub portion of one of the members 13. Thus 35 suitable lubricating oil may be fed under pressure through the duct 23 and passage 24 for distribution to the various bearing parts of the drum supporting roller whereby the latter are kept continuously lubricated.

40 In Figure 5 of the drawings I have shown an oscillatably or universally movable roller 26 mounted upon the upper end of a vertically positioned shaft 27 arranged in a suitable support 28. The vertically disposed 45 peripheral face of this roller is adapted to contact with the periphery of an annular strut member 29 fixed to the end of the drum, and whereby shifting movement of the drum in the direction of its axis 50 is prevented. In this case, a single member 13' is arranged at the lower side of the roller bearing 11' and co-operates with the flange member 14' to provide suitable guiding surfaces for the member 9' carried by the roller 55 in the oscillating movements thereof.

From the above description, it will be readily understood that in the event of deflection of the guide band or ring on the drum due to unequal heating and buckling 60 of the wall, the rollers 8 will follow such

angular displacement of the guiding ring, since they may freely pivot or oscillate relative to the fixed shaft 12. Also by properly operating the wedge members 19, the shafts 12 can be easily adjusted to maintain the desired parallel relation between the peripheral surfaces of the rollers and the faces of the bands or rings 6. Such adjustment I have found to be of very great importance and to enable such drums to be operated 70 with maximum efficiency and economy while at the same time materially increasing the durability thereof.

From the foregoing description considered in connection with the drawings, the 75 construction, manner of operation and several advantages of the present invention will be readily understood. While I have herein shown and described a simple and satisfactory embodiment of the invention, it will 80 nevertheless be understood that the device may also be embodied in various other alternative constructions and I accordingly reserve the privilege of adopting all such legitimate changes in the form, proportion 85 and relative arrangement of the several parts as may be fairly embodied within the spirit and scope of the invention as claimed.

I claim—

1. A setting for revolving drums consisting of spaced rotatable supports, an axis for each rotatable support, and a universally oscillatable mounting between each rotatable support and its axis.

2. A setting for revolving drums consisting of spaced rotatable supports each universally oscillatable relative to its axis of rotation, and means for adjusting the roller shaft to vary the angular relation between the axis thereof and the axis of the drum 100 and maintain a parallel contacting relation between the peripheral surface of the roller and the contacting surface on the drum.

3. A setting for revolving drums comprising rollers each mounted upon a non-rotatable shaft for universal oscillating movement, adjustable bearing members upon which the ends of said shafts respectively have rocking engagement, and means for vertically adjusting the bearing members independently of each other to vary the angular relation of the roller shaft with respect to the drum axis and thereby maintain the peripheral surface on the roller in parallel relation to the contacting surface on the drum.

In testimony that I claim the foregoing as my invention, I have signed my name hereto.

ALBIN BERTHOLD HELBIG.
